CLAIM

The ornamental design for a showerhead, as shown and described.

DESCRIPTION

FIG. 1 is a top, right front perspective view of a showerhead according to our new design;

FIG. 2 is a front elevational view thereof;

FIG. 3 is a right side elevational view thereof, the left side elevational view thereof being a mirror image of the right side shown;

FIG. 4 is a top plan view thereof; and,

FIG. 5 is a rear elevational view thereof.

The broken line representations in the figures of the drawings are for the purpose of illustration only, and form no part of the claimed design.

In a preferred embodiment, the nature of this product is as a plumbing fixture in the form of a showerhead primary useful for washing body parts.
